CLAIM

I claim the ornamental design for a dual-handled drive wrench, as shown and described.

DESCRIPTION

FIG. 1 shows a top perspective view of a dual-handled drive wrench of the present invention.

FIG. 2 shows a front elevation view of the dual-handled drive wrench of FIG. 1.

FIG. 3 shows a back elevation view of the dual-handled drive wrench of FIG. 1.

FIG. 4 shows a right elevation view of the dual-handled drive wrench of FIG. 1.

FIG. 5 shows a left elevation view of the dual-handled drive wrench of FIG. 1.

FIG. 6 shows a top plan view of the dual-handled drive wrench of FIG. 1; and,

FIG. 7 shows a bottom plan view of the dual-handled drive wrench of FIG. 1.

The broken lines in the drawings illustrate unclaimed portions of the lighting fixture and form no part of the claimed design.
